UNITED STATES PATENT OFFICE

CHARLES E. DAVIDSON, OF CLINTON, ILLINOIS

TOOL HOLDER FOR GRINDSTONES

Application filed November 25, 1927. Serial No. 235,692.

This invention relates to tool holders for grindstones, and has for its object to provide a device for holding shear blades or other edged tools or articles against a rotary grinding wheel at a desired angle and permitting the article to be moved in an accurate path for the grinding operation.

A further object of the invention is to provide a holder of the character described whereby shear blades or other articles may be ground with any desired bevel and accurately guided so as to avoid liability of injury to the point of the blade in its movement across the face of the grinding wheel.

15 The invention consists of the features of construction, combination and arrangement of parts, hereinafter fully described and claimed, reference being had to the accompanying drawings, in which:—

20 Figure 1 is a view in side elevation of a grinding wheel, showing the application of the invention thereto.

Figure 2 is a view in rear elevation of the same.

25 Figure 3 is a side view of a portion of the grinding wheel, showing a shear blade in section and at the angle it is held for the grinding operation.

Figure 4 is a front-to-rear section through 30 the tool holder, looking toward one end thereof.

Figure 5 is a view similar to Figure 4, looking toward the opposite end of the holder.

35 Figure 6 is a sectional view through the sliding tool carrier bar and its tool clamp and showing a shear blade clamped in position thereby.

Figure 7 is a perspective view of the tool 40 holder.

Figure 8 is a perspective view of the sliding tool carrier bar.

Figure 9 is a perspective view of a modified form of tool holder.

45 In carrying my invention into practice I provide a tool holder 1 in the form of a substantially inverted U-shaped bracket, said bracket comprising a top bar or plate 2 and depending arms 3 and 4. The arm 3 of the 50 bracket is of greater length than and depends

below the arm 4 and is provided at its lower end with a slot 5 for adjustable engagement with a support 6 on the frame of a grinding wheel 7, which support 6 is provided with a screw clamp 8 to engage the arm 3 and clamp 55 it in adjusted position against said support. The slot 5 allows the holder 1 to be adjusted for proper working relationship to the grinding wheel 7 or for coaction with grinding wheels of different diameters.

60 The top plate 2 of the holder 1 is formed with a longitudinal slot 9 extending its full length and opening through its ends and communicating at its opposite ends with slots 10 and 11 formed in the arms 3 and 4. The slots 65 10 and 11 provide seat slots and guides for the reception of a sliding tool carrier bar 12 which is reciprocable therein for moving the article to be sharpened across the face of the grinding wheel, the slot 9 forming a trans- 70 verse slot to permit the bar 12 to be slipped into and out of engagement with the slots 10 and 11, as will be readily understood. The bar 12 is of suitable length for the purpose 75 and provided at one end with an article clamp comprising a fixed clamping member 13 and an adjustable clamping member 14. A bolt 15 passes through the bar and through an opening in the clamping member 14 and is provided with a wing nut 16 whereby said 80 clamping member 14 may be adjusted and held fixed to clamp the article against the member 13. The member 13 has its clamping face provided with gauge pins 17 or the like against which one surface of the article 85 to be clamped may bear to properly center said article in position. In the present instance the device as shown in Figures 2 and 6 is employed for clamping a shear blade 18 in position for the sharpening of its cutting 90 edge.

The slot 10 is of a depth coinciding substantially with the depth of the bar 12, so that it will just snugly receive said bar and permit of its easy sliding movement, while the slot 11 is of much greater depth than the bar so as to permit the bar to be disposed at different working angles for proper adjustment of the article with relation to the face 95 of the grinding wheel 7 and to enable the ar- 100

ticile to be disposed so that edge surfaces of articles having different bevels may be accurately ground. For the purpose of holding the bar from displacement in the slot 10 a latch 19 is provided. This latch is pivotally mounted, as at 20, upon the arm 3 for movement toward and from the slot and is provided with a guard finger 21 arranged to overhang the slot 10 when the latch is in working position. At its lower end the latch is provided with a lug 22 movable in a segmental guide slot 23 in the arm 3 and connected with the arm by means of a coiled spring 24 normally acting to hold the latch in slot closing position. When in such position the finger 21 cooperates with the walls of the slot 10 to form a guide for the bar 12 whereby a straight line motion of the bar is ensured. For the purpose of supporting that portion of the bar lying in the slot 11 an adjustable seat rest 25 is provided. This comprises an L-shaped member pivoted to the arm 4, as at 26, and embodying an arm 25^a normally extending at an angle across the slot 11 and an arm 25^b engaged by an adjusting and set screw 27, whereby the arm 25^a may be vertically adjusted and held in adjusted position. The upper edge of this arm 25^a forms a support against which the lower edge of the bar rides, as shown in Figure 5, and affords a means by which the bar may be supported and guided at this point at any working angle. By adjustment of the rest 25 the bar may be set at the proper angle for the grinding of a beveled surface of a shear blade or other article by movement of the blade across the face of the grinding wheel in such manner that the point of the blade will be guided and prevented from striking against the side of the wheel and becoming damaged, in the event that in the reciprocating movements of the bar the blade is moved beyond the grinding surface, as will be readily understood.

The operation of the device will be apparent to those versed in the art from the foregoing description, and it will be seen that the invention provides a type of holder by means of which shear blades and other articles may be mounted upon a grinding wheel for a sharpening action and operated so as to be sharpened in a ready and expeditious manner, and that the construction is such that the article may be held at any working angle with relation to the face of the grinding wheel and disposed for the sharpening of beveled cutting surfaces of any degree.

In Figure 9 I have shown a modified type of holder 1^a in which the construction is generally the same as that of the holder 1, except that the arms 3^a and 4^a are of the same length and the slot 5 omitted and both arms 3^a and 4^a provided with slots 5^a which are inclined or extend at an oblique angle to the plane of the arms. This construction of

holder is for application to grinders having a pair of spaced tool supports with which the slots 5^a may be engaged, the inclination of the slots adapting the holder 1^a to be adjustable to vary the grinding angle or to adjust the article with relation to the grindstone where grindstones of different sizes are used.

Having thus fully described my invention, I claim:

1. A holder for tools to be ground comprising a substantially inverted U-shaped bracket embodying a top plate and depending arms, said arms being provided with bar receiving slots, the slot of one arm being deeper than the slot of the other arm and the top plate having a longitudinal slot communicating with the slots in the arms, a work carrier bar adapted to be slidably disposed in the slots in the arms and to be inserted therein and withdrawn therefrom through the slot in the top plate, a latch adapted to overhang the shorter slot in one of the arms to prevent displacement of the bar therefrom, and a seat rest on the other arm adjustable at an angle to and across the slot therein and forming a support for that portion of the bar moving through said slot.

2. A holder for tools to be ground comprising a substantially inverted U-shaped bracket embodying a top plate and depending arms, said arms being provided with bar receiving slots, a work carrier bar adapted to be slidably disposed in the slots in the arms and to be inserted therein and withdrawn therefrom through the slot in the top plate, a latch adapted to overhang the slot in one of the arms to prevent displacement of the bar therefrom, a pivotally mounted seat rest on the other arm, and means for adjusting said rest at an angle to the slot in said arm so as to provide a support variable as to height for that part of the bar extending through said slot.

3. A holder for tools to be ground comprising a substantially inverted U-shaped bracket embodying a top plate and depending arms, said arms being provided with bar receiving slots, the slot of one arm being deeper than the slot of the other arm and the top plate having a longitudinal slot communicating with the slots in the arms, a work carrier bar adapted to be slidably disposed in the slots in the arms and to be inserted therein and withdrawn therefrom through the slot in the top plate, a latch adapted to overhang the shorter slot in one of the arms to prevent displacement of the bar therefrom, a pivotally mounted seat rest on the other arm, and means for adjusting said rest at an angle to the slot in said arm so as to form a variable height support for that portion of the bar extending through said slot.

In testimony whereof I affix my signature.

CHARLES E. DAVIDSON.
